UNITED STATES PATENT OFFICE

PERCY Q. WILLIAMS, OF TOLEDO, OHIO, ASSIGNOR TO OWENS-ILLINOIS GLASS COMPANY, OF TOLEDO, OHIO, A CORPORATION OF OHIO

GLASS-ANNEALING LEER

Application filed March 30, 1927. Serial No. 179,504.

My invention relates to improvements in glass annealing leers and particularly to that type in which the annealing medium is forced through a closed path including the annealing chamber and a recuperator, the latter serving to bring the annealing medium to the proper temperature just prior to injection into the annealing chamber. This general arrangement and principle involving 5 circulation and continued use of the annealing medium is disclosed and claimed in my copending application, S. N. 129,373, filed August 16, 1926. Said copending application to some extent discloses but does not contain 10 claims to the feature of circulation an annealing medium beneath the leer conveyor, this feature constituting the subject matter 15 of the present application.

An object of the present invention is to 20 provide exceptionally effective means for heating the bottoms of ware during its passage through an annealing zone so that the temperature in the bottoms of the ware will approximate that in the body and upper portions of the ware. This uniformity of 25 temperature throughout the ware structure materially contributes to uniform tempering or annealing of the ware and minimizes the presence of strains and cracks in the articles 30 being treated. To this end, the leer is so constructed that a longitudinal passageway is formed beneath a length of the ware conveyor and equipped with valves so that the annealing medium rising from the recuperator may 35 be divided, causing a portion to move through the passageway beneath the conveyor while the remaining portion rises into the annealing chamber for direct contact with the ware. Due to the valve control, the 40 heating effectiveness of the construction may be readily varied to meet the particular requirements of the ware being treated.

Other objects will be apparent hereinafter.

In the accompanying drawings: 45 Fig. 1 is a vertical central longitudinal sectional view of the front portion of a leer showing the relation of the bottom passageway to the associated parts.

Fig. 2 is a horizontal sectional view of a 50 portion of the leer showing the return pipe

connections through which the annealing medium is returned to the recuperator for re-heating and injection into the annealing chamber.

Fig. 3 is a transverse sectional view at the 55 line III—III of Fig. 1.

Fig. 4 is a fragmentary sectional elevation showing the valve arrangement in the under-pan passageway.

Referring to the drawings, the leer comprises spaced side walls 5 resting in part upon longitudinal base members 6 formed of channel iron units, said side walls being interconnected at their upper ends by a cover or ceiling 7. The side walls and cover are formed of suitable insulating material held in place by a metal casing 8. The ware receiving end of the leer may be closed by a vertically movable gate 9. An endless ware conveyor 10 is arranged between the walls of the leer and at 70 its front end runs over two vertically spaced sprocket wheels 11. This ware conveyor is preferably in the form of a series of interconnected transverse metal plates or pans spaced 75 apart slightly to permit circulation of an annealing medium as will be hereinafter pointed out.

Arranged between the upper and lower reaches of the ware conveyor at the forward end of the leer is a heating unit including a 80 combustion chamber 12 and a tube recuperator 13. Obviously, a recuperator other than the tube type may be employed if desired. This unit is of a type similar to that disclosed in my copending application, S. N. 129,373, filed August 16, 1926. In the present application, the recuperator is spaced a greater distance below the upper reach of the conveyor than in the copending application referred to and the top casting 40 of the recuperator 90 13 is enlarged at its forward end to provide a seal 14 directly over the combustion chamber 12.

The lower ends of the recuperator tubes 95 communicate directly with a chamber 15 whose rear end opens into a transverse pipe 16 leading from a suction fan 17 at one side of the leer. This fan 17 has pipe connection with a central longitudinal return pipe 18 with a valve controlled suction boxes 19 100

spaced along the leer tunnel provide communication between the ware receiving tunnel 20 and the return pipe 18. Through operation of the suction fan 17, a continuous circulation of hot air or other annealing medium is set up through any selected suction box or boxes 19, the return pipe 18, and the recuperator tubes.

Arranged directly over the return pipe 18 and extending longitudinally of the leer, is a partition 21. This partition comprises metal top and bottom plates 22 and 23, respectively, the former being arranged in a plane with the top casting of the recuperator whereby 15 an under-pan passageway 24 is formed extending from the front end seal 14 to a point just beyond the suction box 19 remote from the receiving end of the leer. At this point, the under-pan passageway is closed by increasing the thickness of the partition 21 which is preferably formed of suitable insulating material.

The ware conveyor is maintained in proper spaced relation with the top plate 22 of the 25 horizontal partition 21 by a series of rollers 25 which also serve to reduce friction between the conveyor and its support. Arranged at intervals along the under-pan passageway 24, is a set of transversely extending 30 valves which are individually adjustable to control the extent of movement of the annealing medium through said passageway. These valves each include a transverse operating and carrying rod 26, journaled in the 35 side walls 27 and in a bushing 28, said rod mounting at its outer end an operating crank 29 which may be manually moved to adjust the position of the valve. This valve also includes transversely aligned plates 30 40 which are suitably connected to the valve rod 26 so that rotation of the latter will change the angle of the plates and thereby eliminate any desired portion of the passageway from the path of circulation of the annealing 45 medium or vary its heating effectiveness.

In operating a leer constructed as above set forth, the ware is fed into the annealing chamber in the usual manner and is slowly moved through the annealing chamber toward the delivery end of the leer tunnel 20. The annealing medium is circulated under influence of the suction fan 17 and during its circulation moves upwardly through the recuperator tubes wherein it is brought to 55 the proper temperature and thence rises through the spaces between the ware conveyor pans or plates and into direct contact with the ware being treated. This annealing medium, together with the heat rising 60 from the ware itself, is drawn into one or more of the suction boxes 19 depending upon the position of the suction box valves 35. From the suction boxes, the annealing medium is returned to the recuperator by way 65 of the return pipe 18 and the fan 17.

In the event the ware being handled is of that type in which the bottoms are exceptionally heavy, it is desirable to cause application of additional heat to the heavy bottoms so that the ware structure will be 70 uniformly heated in the annealing chamber. Under these circumstances, the valves in the under-pan passageway 24 will be adjusted

so that a portion of the annealing medium will be drawn rearwardly beneath the pans a distance governed by the length of the annealing zone or period of time required to bring the ware bottoms to the proper temperature. By so dividing the annealing medium, the conveyor pans and ware bottoms 75 may be brought to the desired temperature at which the ware bottoms and body portions are uniformly heated. By adjusting the valves 30, as shown for example in Fig. 1, a portion of the annealing medium will be directed through the under-pan passageway to the second valve 30. Between the recuperator and the second 80 valve 30 in the under-pan passageway, the annealing medium rises into the leer tunnel in the usual manner, but due to the rearward movement of a portion of the hot annealing medium beneath and in direct contact with the conveyor pans, said pans and the contacting bottoms of the ware are brought to the 85 desired temperature. By adjusting the second valve in said passageway at substantially the angle shown in Fig. 1, a portion of the annealing medium will be carried on back to the last valve to thereby prevent a too 90 rapid drop in the temperature of the conveyor pans and ware bottoms. Obviously, these valves may be adjusted to vary the extent of movement of the annealing medium through the under-pan passageway. The 95 valves 35 in the suction boxes 19 and the valves 30 in the under-pan passageway may be so relatively adjusted that the annealing zone above the conveyor and the effective 100 length of the passageway 24 are of corresponding length or vary as required by the 105 type of ware being treated. Medium weight bottoms may require only a slight additional heating and if this ware has heavy body portions, the annealing zone in the space above 110 the conveyor may be lengthened beyond the effective limit of the passageway, causing 115 extra application of heat to the body portions and uniform heating of the ware structure.

Manifestly, certain minor changes may be resorted to within the spirit and scope of the appended claims.

What I claim is:

1. A glass annealing leer comprising an annealing chamber, a ware conveyor, a heating unit at the forward end of the annealing chamber, means causing a continuous circulation in a closed path, of an annealing medium free from products of combustion, said 125

path extending through the annealing chamber and heating unit, and means causing movement of a portion of the annealing medium a predetermined distance rearwardly beneath the conveyor.

5. 2. A glass annealing leir comprising an annealing chamber, a ware conveyor, a heating unit at the forward end of the annealing chamber, means causing a continuous circulation in a closed path, of an annealing medium free from products of combustion, said path extending through the annealing chamber and heating unit, means causing movement of a portion of the annealing medium 10 rearwardly beneath the conveyor, and valve means for controlling the extent of such movement.

20. 3. A glass annealing leir comprising an annealing chamber, a ware conveyor, a heating unit at the forward end of the annealing chamber, suction boxes communicating with the annealing chamber and arranged in a closed path including the heating unit, means causing circulation of an annealing medium 25 through the heating unit, annealing chamber and suction boxes, and means causing movement of a portion of the annealing medium a predetermined distance rearwardly beneath the conveyor.

30. 4. A glass annealing leir comprising an annealing chamber, a ware conveyor, a heating unit at the forward end of the annealing chamber, suction boxes communicating with the annealing chamber and arranged in a closed path including the heating unit, means causing circulation of an annealing medium through the heating unit, annealing chamber and suction boxes, means causing movement 35 of a portion of the annealing medium rearwardly beneath the conveyor, and valves arranged at intervals along and beneath the conveyor, said valves being adjustable to cause upward movement of the annealing medium through the ware conveyor.

45. 5. A glass annealing leir comprising an annealing chamber, a ware conveyor, a heating unit at the forward end of the annealing chamber, a partition spaced below the ware conveyor to form a longitudinal passageway below the latter, means providing communication between the heating unit and said passageway, means for causing a continuous circulation of an annealing medium 50 in a closed circuit extending through the annealing chamber, heating unit and said passageway, and means in the annealing chamber and said passageway operable independently of each other to control the relative degrees of movement of the annealing medium 55 through the annealing chamber and said passageway.

6. 6. A glass annealing leir comprising an annealing chamber, a ware conveyor, a heating unit at the forward end of the annealing chamber, a partition spaced below the ware

conveyor to form a longitudinal passageway below the latter, means providing communication between the heating unit and said passageway, means causing circulation of an annealing medium through the annealing chamber and said passageway, and valve mechanism in said passageway operable to control the extent of movement of the annealing medium through said passageway.

7. 7. A glass annealing leir comprising an annealing chamber, an endless ware conveyor, a partition spaced below the ware conveyor forming a longitudinal passageway between the partition and conveyor, a heating unit at the forward end of the annealing chamber, means causing circulation of the annealing medium through the passageway and said chamber, and means communicating with the annealing chamber for returning the annealing medium from said chamber and passageway to the heating unit.

20. 8. A glass annealing leir comprising an annealing chamber, an endless ware conveyor, a partition spaced below the ware conveyor forming a longitudinal passageway between the partition and conveyor, a heating unit at the forward end of the annealing chamber, means causing circulation of the annealing medium through the passageway and said chamber, means communicating with the annealing chamber for exhausting and causing return of the annealing medium from said chamber and passageway to the heating unit, and means for varying the effective length of 25 said passageway.

9. 9. A glass annealing leir comprising an annealing chamber, an endless ware conveyor, a partition spaced below the ware conveyor forming a longitudinal passageway between the partition and conveyor, a heating unit at the forward end of the annealing chamber, means causing circulation of the annealing medium through the passageway and said chamber, means communicating with the annealing chamber for exhausting and causing 100 return of the annealing medium from said chamber and passageway to the heating unit, and valve means for varying the heating effectiveness of the passageway.

10. 10. A glass annealing leir comprising an annealing chamber, an endless ware conveyor, a recuperator including a heating unit spaced below the forward end of the conveyor providing a passageway therebetween, a partition extending rearwardly in a plane 115 with the upper side of the recuperator providing a rearward extension of said passageway, means closing the opposite ends of said passageway, and means causing circulation of an annealing medium through the annealing chamber and a variable length of said passageway.

11. 11. A glass annealing leir comprising an annealing chamber, an endless ware conveyor, a recuperator including a heating unit 120

spaced below the forward end of the conveyor providing a passageway therebetween, a partition extending rearwardly in a plane with the upper side of the recuperator providing a rearward extension of said passageway, means closing the opposite ends of said passageway, means causing circulation of an annealing medium through the recuperator, the annealing chamber and said passageway, and means adjustable to vary the extent of movement of the annealing medium through said passageway.

12. In an annealing leer, the combination of a leer tunnel, a traveling conveyor extending lengthwise therethrough, a heating device for heating an annealing medium, said heating device including means for preventing direct contact between the annealing medium and the heating medium in said heating device, and means for causing said annealing medium to move lengthwise of the conveyor in contact with the under side thereof.

13. An annealing leer comprising a leer tunnel, a traveling ware conveyor extending lengthwise through the leer, means forming with said conveyor a passageway extending lengthwise thereof beneath the conveyor, said conveyor forming an upper wall or cover for said passageway and formed with restricted openings for the passage of an annealing gas, means for heating said gas, and means to cause a portion of said gas to flow through said passageway lengthwise thereof and a portion to move upward through said restricted openings.

14. An annealing leer comprising a leer tunnel, a traveling ware conveyor extending lengthwise through the leer, means forming with said conveyor a passageway extending lengthwise thereof beneath the conveyor, said conveyor forming an upper wall or cover for said passageway, and formed with restricted openings for the passage of an annealing gas, means for heating said gas, means to cause a portion of said gas to flow through said passageway lengthwise thereof and a portion to move upward through said restricted openings, and adjusting means to adjustably vary the distance through which the annealing gas is carried lengthwise of said passageway.

15. An annealing leer comprising a leer tunnel, a traveling ware conveyor extending lengthwise through the leer, means forming with said conveyor a passageway extending lengthwise thereof beneath the conveyor, said conveyor forming an upper wall or cover for said passageway and formed with restricted openings for the passage of an annealing gas, means for heating said gas, means to cause a portion of said gas to flow through said passageway lengthwise thereof and a portion to move upward through said restricted openings, adjusting means to adjustably vary the distance through which the annealing gas is

carried lengthwise of said passageway, and separate adjusting means to adjustably regulate the amount of the annealing gas passing through said restricted openings.

Signed at Toledo, in the county of Lucas 70 and State of Ohio, this 26th day of March, 1927.
